LINE SETTING AND CASTING MACHINE.

1,066,086.

Specification of Letters Patent.

Patented July 1, 1913.

Application filed August 22, 1910. Serial No. 578,459.

To all whom it may concern:

Be it known that I, HEINRICH DEGENER, a resident of 26 Hollmannstrasse, Berlin, German Empire, manager, having invented 5 certain new and useful Improvements in or Relating to Line Setting and Casting Machines, do hereby declare that the following is an exact specification of the same.

This invention relates to improvements in 10 line setting and casting machines of the known Mergenthaler system, and has particular reference to the collector mechanism.

The accompanying drawings show by way 15 of example constructions according to this invention, namely—

Figures 1-3 show the collector mechanism, Fig. 1 being the first construction in front elevation, Fig. 2 a cross-section through the conduit for the transfer of the 20 matrices from the collector carriage to the casting carriage, and Fig. 3 the second construction in front elevation.

The collector carriage 1 is provided with two stops or ledges 2 3 which, unlike former 25 constructions, are stationary and preferably are made in one piece with the collector. The setting of the matrices X is effected in the known manner, but the matrices are all collected on the upper fixed ledge 2, so that 30 after the line is finished, it stands on the above-mentioned upper ledge or stop. If the whole line is to be set in italics, the collector is raised in the known manner, and the line despatched. If, on the contrary, the 35 whole line is to be set in ordinary type, the collector is not raised so high, and is lower to the extent of the distance between the two characters on the matrices, since the matrices in the casting carriage have to stand for the 40 purpose in a lower position and the line is then conveyed to the casting carriage.

In order to release the machine sometimes in the higher, and sometimes in the lower position, and at the same time to limit the 45 travel, the known pin 4 which, after the raising of the collector carriage, contacts with the catch 20 and releases in the known manner the device for the further conveyance of the matrices, is arranged in an ad- 50 justable manner. It can be arranged at a

higher or lower level for instance by a bell crank lever 5. The bell crank lever 5 itself is provided with a handle 6 for operating it. When the lever 5 is in the position shown dotted in Fig. 1, the pin 4 is in its lowest position, the release takes place in the ordinary manner, and the whole line is cast in italics, but if the lever 5 is in the position shown in full lines, the pin 4 strikes the releasing device earlier, and consequently limits the upward movement of the collector carriage and releases the device for the further conveyance of the matrices at a correspondingly earlier moment. When the collector carriage is raised into relation to the organ to 60 which the assembled line is transferred, it is temporarily held in such position by the engagement of the hook 7 with the machine frame. This hook is constructed and operates in the manner shown in numerous patents, such for instance as that to A. D. Pentz, No. 545,530, September 3, 1895. In view of the fact that the collector carriage is brought into operative relation to the said organ in a plurality of positions, the hook 7 65 is herein shown as formed with a corresponding plurality of engaging teeth. The collector carriage has or may have the usual construction and mode of operation, it being adapted to be raised from the assembling to 70 the transfer position by any desired means, such for instance as those disclosed in the patent to O. Mergenthaler, No. 436,532, Sep- 75 tember 16, 1890. If mixed type is to be set, the front folding bracket 8 pivoted at 88 to 80 the collector carriage is folded forward, after the line has been collected in the above described manner on the upper ledge 2, and those matrices which are to be set in ordinary type, are brought in the known man- 85 ner, by turning over, into their bottom position, so that they stand within their lugs on the bottom ledge 3, whereupon the carriage is raised, and at the same time the lever 5 must be set for italics. In that case 90 the matrices are transferred in the desired manner at two different levels from the collector carriage to the casting carriage. It is further necessary to have a device in order 95 to transfer the spacers Y into the casting 100

carriage always at the same level, whether the collector carriage is in its upper or lower position. To that end, the conduit 85 through which the spacers are transferred from the collector carriage to the casting carriage, is widened in front, namely in such manner that when the collector carriage is raised only into its bottom position, the bottom edges of the spacer lugs come into engagement with the oblique bottom conduit surface, and the spacers are raised during the further transport, while the matrices retain their position. When setting in italics, the spacers travel in the ordinary manner in the horizontal direction.

If it is desired to avoid the wear of the spacer lugs or of the intermediate conduit, due to the coöperation or contact of the said parts, the arrangement may be made as shown in Fig. 3. In this arrangement, the distance between the upper edge of the catching ledge 2 from the upper edge of the bracket 8 on which, as is known, the spacers with their lugs stand, is increased to the extent of the distance between the two kinds of characters, consequently, after the setting of the line, the position of the spacers relatively to the position of the matrices is such as is to be occupied by the matrices in the casting carriage when ordinary type alone is being set. In setting ordinary type, therefore, no movement of the spacers relatively to the matrices in the transfer conduit from the collector carriage to the casting carriage is required. If, however, italics or mixed matter are to be set, the spacers will be too high relatively to the matrices, and it will be necessary to bring them down. To that end, as shown in Fig. 3, the conduit for the transfer of the spacers is tapered in the opposite direction, that is to say, its bottom surface is horizontal, while the upper surface is rising. In that way, a relative movement between the spacers and the matrices is insured only in the case of lines with italics which occur comparatively rarely. The same result as described can be of course obtained also by raising the collector always to the same level, and modifying instead the position of the intermediate conduit or of the casting carriage. The device can be used in a corresponding manner also for collecting more than two kinds of type.

Having now particularly described and ascertained the nature of my invention and in what manner the same is to be performed, I declare that what I claim is:

1. In a typographical machine, in combination with multiple face matrices, the collector carriage provided with means for supporting the matrices at different levels and also means to trip one of the machine devices, the said tripping means being adjustable to permit the movement of the collector carriage to different extents.

2. In a typographical machine, in combination with multiple face matrices, the collector carriage provided with means for supporting the matrices at different levels and also means to arrest the collector carriage in different positions, said arresting means serving also to trip one of the machine devices.

3. In a typographical machine, in combination with multiple face matrices, the collector carriage provided with means for supporting the matrices at different levels and also means carried thereby to arrest the collector carriage in different positions.

4. In a typographical machine, the combination with a collector carriage, an adjacent organ to which the assembled line is transferred, and means whereby the said carriage is brought into operative position with relation to the said organ at different levels, the said carriage being formed with spacer supporting means at one level and the said organ being formed with spacer supporting means adapted to receive the spacers from the said carriage in any of the said operative positions.

5. In a typographical machine, the combination with a collector carriage, an adjacent organ to which the assembled line is transferred, and means whereby the said carriage is brought into operative position with relation to the said organ at different levels, the said carriage being formed with spacer supporting means at one level, and the said organ being formed with a spacer supporting groove having a flared end adapted to receive the spacers from the said carriage in any of the said operative positions.

6. In a typographical machine comprising multiple face matrices, the collector carriage to receive the matrices and provided with means to trip one of the machine devices, the said tripping means being adjustable to permit the movement of the collector carriage to different extents.

7. In a typographical machine comprising multiple face matrices, the collector carriage to receive the matrices and provided with means to arrest the collector carriage in different positions, the said arresting means serving also to trip one of the machine devices.

8. In a typographical machine comprising multiple face matrices, the collector carriage to receive the matrices and having means carried thereby to arrest the collector carriage in different positions.

9. In a typographical machine comprising multiple face matrices, the combination of the collector carriage to receive the matrices, and means for controlling the extent of movement of the collector carriage and for tripping one of the machine devices, irrespective of the extent of movement of the collector carriage.

10. In a typographical machine comprising multiple face matrices, the combination of the collector carriage to receive the matrices and arranged to be moved to different extents, and means to trip one of the machine devices, irrespective of the extent of movement of the collector carriage.

In witness whereof I hereunder set my hand in the presence of two witnesses.

HEINRICH DEGENER.
